UNITED STATES PATENT OFFICE.

FRED PATEE, OF PEORIA, ILLINOIS.

DESIGN FOR A SPROCKET-WHEEL.

SPECIFICATION forming part of Design No. 30,038, dated January 17, 1899.

Application filed October 18, 1898. Serial No. 693,933. Term of patent 7 years.

To all whom it may concern:

Be it known that I, FRED PATEE, a citizen of the United States, residing at Peoria, in the county of Peoria and State of Illinois, have ⁵ invented and produced a new and original Design for Sprocket-Wheels, of which the following is a specification, reference being had to the accompanying drawings, forming a part thereof.

16 Figure 1 is a plan view of a sprocket-wheel, showing my design. Fig. 2 is a cross-section on the line X X, Fig. 1. Fig. 3 is a cross-section on the line Y Y, Fig. 1.

As shown in the drawings, the leading or ¹⁵ material features of my design consist of the centrally-disposed ring *a*, the radiating short spokes *b*, the substantially rectangular-shaped extensions *c* thereof, the central body thereof presenting a substantially rectangular

open space; the bars *d*, connecting the spoke extensions *c*, forming a substantially rectangular-shaped frame, the parts thus combined forming a Maltese cross, the circular peripheral rim *e*, meeting the ends of the spoke extensions, the segments of the circular rim between the spoke extensions, together with the bars *d*, forming a boundary for the open space *f*, as shown in the drawings, and the teeth, as shown, upon the peripheral rim.

Having described my invention, what I ²⁰ claim as new, and desire to secure by Letters Patent, is—

The design for a sprocket-wheel, as herein shown and described.

FRED PATEE.
